CLAIM

The ornamental design for a top plate for rack, as shown and described.

DESCRIPTION

FIG. 1 is a front, side, perspective view of a top plate for rack showing our new design;

FIG. 2 is a top view thereof;

FIG. 3 is a bottom view thereof;

FIG. 4 is a front view thereof, the rear view being identical;

FIG. 5 is a side view thereof, the opposite side view being identical; and,

FIG. 6 shows a perspective view thereof, with environmental material shown in broken lines.

The broken line showing of environmental material is for illustrative purposes only and forms no part of the claimed design.
